UNITED STATES PATENT OFFICE

OTIS D. TREIBER, OF NARBERTH, PENNSYLVANIA, ASSIGNOR TO TREIBER DIESEL ENGINE CORPORATION, OF CAMDEN, NEW JERSEY, A CORPORATION OF NEW JERSEY

LIQUID FUEL FEEDING MEANS FOR INTERNAL COMBUSTION ENGINES

Application filed March 31, 1927. Serial No. 179,820.

In the operation of internal combustion engines of the Diesel type in which liquid fuel, such as oil, is employed the fuel must be supplied in the form of a spray at high velocity and high pressure, as is known. The fuel also must be sprayed into the cylinder at proper intervals and during periods in which the piston occupies a certain definite relation to the top dead center position of the crank shaft. Each period of admission or discharge of fuel into the cylinder begins at a time when the piston is in position with the crank arm of the crank shaft in advance of the top dead center 15 position thereof and continues until the said crank has traveled or moved to a point beyond its top dead center position. Usually the admission of fuel begins when the crank arm is approximately ten (10) to eight (8) 20 degrees in advance of its top dead center position and continues until it has moved to a point approximately eighteen (18) degrees beyond such dead center position.

The invention relates to means whereby 25 the functions and operations above indicated may be effected in a simple and efficient manner.

The general object of the invention is to provide improved means of novel construction 30 whereby liquid fuel may be discharged or delivered most efficiently in the form of a spray into the cylinder of an internal combustion engine during the proper periods with respect to the positions of the piston 35 in said cylinder.

It also is an object of the invention to provide means of novel construction whereby at the beginning of each period the liquid will be discharged initially at high speed 40 and under high pressure and will so continue to the end of the period at which time the discharge of fuel will be terminated instantaneously.

Another object of the invention is to provide means of novel construction whereby the discharge of liquid fuel into cylinders of internal combustion engines may be regulated and controlled automatically so as to maintain the speed of operation of an engine at a substantially constant rate.

A further object of the invention is to provide means of novel construction whereby the length of the periods during which liquid fuel is discharged into the cylinders of internal combustion engines may be controlled.

I shall not at the present time undertake to enumerate and point out all of the various objects and advantages incident to my invention but other and further objects 60 thereof will be pointed out in the detailed description thereof which follows, or will be apparent from such description.

In order that the invention may be readily understood and its advantages from a practical view point fully appreciated reference should be had to the accompanying drawings in which I have illustrated one form of a convenient mechanical embodiment 65 thereof. However, it is obvious that various 70 changes in the mechanical details may be made within the scope of the claims without departing from the spirit and principle of the invention as defined in the claims.

In the drawings,

Fig. 1 is a view in central longitudinal section of the upper or head portion of the cylinder of an internal combustion engine and the piston operating therein and showing also a spray nozzle partly in elevation and partly in longitudinal section and also showing partly in section and partly in elevation the means employed for operating the said nozzle to discharge liquid fuel therefrom in the form of a fine spray into the cylinder of the said engine;

Fig. 2 is a view in central longitudinal section of the spray nozzle shown in Fig. 1; and

Fig. 3 is a view in transverse section taken on the line 3-3 of Fig. 2.

In the drawings I have shown a cylinder 1 of an internal combustion engine surrounded by a water jacket structure 2. A piston 3 of any suitable known construction operates within the cylinder 1 in the usual manner.

A spray nozzle indicated at 5 projects at its inner or discharge end through an open-

ing 6 into the top of the cylinder as is clearly shown in Fig. 1.

The spray nozzle comprises a casing 10, as clearly indicated in Fig. 2 of the drawing, 5 which casing includes a portion of relatively large internal and external diameter and also a reduced inner end portion, the latter being indicated at 11. The relatively large portion of the casing is provided with 10 a relatively large axial opening or passageway 12 from which a relatively small passageway 13 leads through the reduced portion 11. The passageway or opening 13 is in axial alignment with a like opening 13^a provided in a member 13^b removably held 15 in engagement with the lower end of the reduced portion 11 by means of a holding cap 13^c. The passageway 13^a (in alignment with the passageway 13, as stated) terminates at its inner or lower end in a tapered portion 14 which constitutes a valve seat. Leading from the bottom of the tapered portion 14 is a much smaller axial opening or 20 passageway 15 from the inner end of which lead very small lateral discharge passageways 16, so small relatively speaking as to be almost capillary in their dimensions. It is from these last mentioned openings 25 that the liquid fuel is discharged in the form of a fine spray. In fact, as discharged the fuel has the appearance of a vapor.

The opening at the inner end of the nozzle 5 may be closed by means of a tapered valve 17 which is adapted to fit or seat 30 against the tapered seat 14. The stem 18 of the valve which extends through the passageway 13 has an external diameter less than the internal diameter of the said passageway 13. This relation between the stem 35 18 and passageway or opening 13 is shown in Fig. 2 of the drawings. The upper or outer end of the stem 18 is connected, preferably integrally, with an enlarged tubular portion 20 which is slidably supported 40 within the passageway or opening 12 of the casing 10. The lower or inner end of the portion 20 terminates in a tapered portion as indicated at 21. The outer surface of the tapered portion 21 is in parallel relation to 45 the correspondingly shaped surface 22 at the inner or lower end of the relatively large opening 12 in the casing 10. The tapered portion 21 is provided with openings 21^a as shown through which liquid fuel is adapted 50 to escape from the portion 20 into the lower end of the passageway 12 of the casing 10. In other words, fuel is admitted through the said openings 21^a into the space between the tapered portion 21 and the inclined or 55 tapered surface 22. The upper end of the slideable portion 20 projects beyond the upper end of the casing 10 and is screw threaded as indicated at 23 with which screw threaded portion adjustable bearing nuts 24 are connected. The slideable portion 20 is provided

intermediate its ends with an annular relatively wide groove or depression 25 and also with radial openings 26, only two of which are shown. Preferably there are four of these openings and they are in alignment with similar openings 27 through the walls of a tubular plunger 30. The said plunger likewise is provided with an annular relatively wide groove or depression 31 inwardly of and in opposed relation to the smaller groove or depression 25 in the portion 20. The lower half portion of the plunger 30 is provided with a relatively large axial opening 35 while the upper half portion thereof is provided with a relatively small axial opening 36.

The casing 10 is provided with an annular flange-like portion 37 which is provided with an opening as indicated at 38 which is in communication with the annular shallow groove or depression 25. The inner end of a pipe 39 is connected with the said opening 38 and through the said pipe liquid fuel is adapted to be supplied to the annular shallow groove or depression 25. From the latter the fuel flows through the openings 26 and 27 into the axial passageway 35 of the plunger 30.

The lower end of the passageway or opening 35 is flared or tapered outwardly as indicated at 40 to provide a seat for a valve 41 having a stem 42 through which and through the said valve a central axial opening 43 is provided. Radial openings 44 are provided in the said stem as shown the inner ends of which openings are in communication with a slightly enlarged portion 45 of the opening 43 previously referred to. The tubular valve stem 42 is provided with longitudinally extending grooves 46. Preferably there are not less than four of these grooves. The enlarged opening 45 which extends through the valve 41 is flared or tapered outwardly as indicated at 48 to form a seat for a valve 49 upon the lower end of a rod 50 which extends through the opening 43, the opening 35, and through the opening 36 in the upper half end portion of the plunger 30. The said rod extends beyond the upper end of the plunger 30 and is provided at its upper end with adjustable nuts 51 against which the upper end of a coiled spring 52 is seated, the lower end of which spring rests upon the upper end of the plunger 30. The spring 52 is normally under compression tending to cause inward movement of the plunger 30 and outward movement of the rod 50.

The plunger 30 is provided at its upper end with a flange 55 the outer edge of which has a downwardly extending narrow flange 56. A relatively heavy coiled spring 57 extends around the portion of the plunger 30 beyond the outer end of the tubular portion 20 and its upper end is seated against the

under side of the flange 55. Its lower end is seated against the upper side of the uppermost of the adjustable nuts 24 to which previous reference has been made. The 5 spring 57 is under compression and tends to cause outward or upward movement of the plunger 30 and downward or inward movement of the portion 20 to hold the valve 17 in closed position against its seat 14. Outward movement of the plunger 30 is limited 10 by engagement of the flange 55 thereof with an inwardly extending flange 60 upon the upper end of a tubular casing 61 the lower end of which is internally screw threaded 15 and in engagement with an externally screw threaded upper end portion of the casing 10 as shown in Fig. 2 of the drawings. The coil 57 previously referred to is located within the casing 61. The said casing is provided 20 with openings 62 therein through which access may be had to the nuts 24 for the purpose of adjusting the same. The lower ends of the openings 62 are located a short distance above the upper or outer end 25 of the casing 10.

The upper end of the casing 10 is provided with an annular groove 65 from which leads a passageway 66 the outer end of which is in communication with a pipe 67 through 30 which leakage or waste liquid fuel may be conducted.

Liquid fuel is discharged from the nozzle through the small lateral passageways 16 previously referred to as a result of the 35 operation of the plunger 30 and is controlled by the cooperation of certain portions of the nozzle mechanism with the said plunger as hereinafter will be described.

For the purpose of operating the plunger 40 30 I have provided a lever 70 pivoted intermediate its ends upon a stationary pivot 71 supported upon the upper end of a standard 72 which rises from the head 73 of the cylinder 2. The outer end of the lever 70 is provided 45 with a roller 74 which bears against a cam disk 75 mounted upon a cam shaft 76 which rotates during the operation of the engine. The said cam disk is provided with a cam projection 77 which is adapted to contact once during each revolution of the cam shaft 76 with the roller 74 to actuate the lever 70 to cause pivotal movement thereof. When the cam rise or projection 77 strikes the roller 74 the outer end of the lever is 55 lifted to cause inward movement of the inner end thereof. The inner end of the lever 70 is slotted or bifurcated to form two parallel arms 80 each of which is provided upon its lower or inner edge with a projection 81 which is of wedge shape as shown in Fig. 1 60 of the drawings. The lower edges of these wedge shaped projections rest against the top of the flange 55 previously referred to. The arms 80 extend beyond the projections 65 81 previously referred to and are provided

with horizontal slots or notches as indicated at 82.

A lever 83 is provided which lever is pivotally mounted upon an eccentric 84 which eccentric is secured to the shaft 85 70 which shaft is journaled in bearings upon the upper ends of posts or standards 86 which rise from the cylinder heads. As illustrated in Fig. 1 of the drawings, the eccentric is positioned with its thickest or 75 highest part projecting in horizontal direction toward the right. The shaft 85 is adapted to be oscillated in one direction or the other by means of a lever only a portion of which is shown at 87. The said lever 80 may be actuated or operated manually to oscillate or move the shaft 85 with the eccentric thereon in one direction or the other as may be necessary to regulate and control the speed of the engine. If desired 85 the said lever may be connected with the engine governor so as to be automatically controlled by movements of the said governor.

If the shaft 85 together with the eccentric 90 84 shown thereon should be turned to the right through say 90° it will be apparent that the end of the lever mounted upon the said eccentric will be depressed through a distance depending upon the height of the 95 eccentric. Such movement or depression will cause an upward or outward movement of the inner end of the lever 83 because of the fact that the said lever is provided with and pivoted upon lateral projections 88 intermediate its ends which projections extend into the slots 82 in the arms 80 to which previous reference has been made. If the shaft and eccentric were turned in the opposite direction the outer or pivot end of the lever 83 would be elevated to cause inward or downward movement of adjustment of the inner end of the said lever. The inner end portion of the said lever is so formed as to extend slightly upwardly or away from 100 the outer end of the nozzle structure. This is shown clearly in Fig. 1 of the drawings. The inner swinging end of the lever 83 is provided with a screw threaded opening 89 in which is mounted an adjustable pin or 105 device 90 for regulating the operation of the nozzle valve, the inner end of which device is adapted to contact with the outer end of the rod 50. The said device 90 may be locked in any position to 110 which it may be adjusted by means of a locking nut 91. In Fig. 1 of the drawings the inner end of the adjustable device 90 is shown in position spaced a short distance from the outer end of the rod 50. 115

I shall now describe briefly the operation of the liquid fuel feeding means embodying my invention as previously described herein.

In describing the operation it will be 130

understood and assumed that liquid fuel is supplied under relatively low pressure—say 35 or 40 pounds to the square inch—from the pipe 39 through the opening 38 and through the openings 26 and 27 into the opening or passageway 35 in the plunger 30. From the latter the fuel passes by the valve 41 into the opening or passageway within the portion 20 and from the latter through the openings 21^a and thence into the relatively small axial passageway or opening 13, but is prevented from escaping from the latter through the openings 16 by means of the valve 17.

In the operation of the engine the cam shaft 76 rotates so that the cams thereon operate to cause pivotal movement of the lever or levers 70 once during each revolution of the shaft. It will be understood that there is one lever for each cylinder of the engine structure. Upon elevation of the outer end of the lever 70 the inner end thereof is caused to move inwardly and the projections 81 being in contact with the outer end of the plunger 30 the latter is caused to move inwardly in opposition to the spring 57. When the plunger thus moves inwardly the valves 41 and 49 together with the rod 50, upon which the latter valve is mounted, move therewith as a unit. As a result of such movement the liquid fuel which has been fed or supplied to the space underneath the plunger is subjected to pressure. Such pressure is exerted through the openings 21^a against the tapered surface 22. The application of pressure through the liquid against the surface 22 produces forces of reaction which act against the opposing tapered surface of the portion 21 to effect outward movement of the portion 20 together with the valve stem or rod 18 to open the valve 17. This opening movement occurs suddenly so that the liquid fuel is discharged from the opening 16 suddenly and under very high pressure. The opening movement of the valve 17 occurs when the piston in the cylinder occupies the proper relation to its top dead center position as herein before indicated.

It will be apparent that the device 90 upon the inner end of the lever 83 will be caused to move inwardly more rapidly than the adjacent portion of the lever 70. Consequently the device 90 will be caused to contact with the outer end of the rod 50 and cause inward movement thereof to lift the valve 49 from its seat 48. When this occurs a reverse flow of the liquid fuel between the valve 49 and its seat is permitted whereupon the spring 57 operates instantly to close the valve 17 to effect sudden stoppage of the discharge of liquid fuel from the nozzle into the cylinder. The point at which this occurs may be regulated and controlled

by adjusting the device 90 upon the inner end of the lever 83.

As has been indicated already, if the eccentric 84 be oscillated in one direction or the other within 90° limits the position of the outer end of the lever 83 will be varied or adjusted to alter the position of the device 90 with relation to the upper or outer end of the rod 50. In the operation of an engine the device 90 will be adjusted into position with respect to the rod 50 to permit or cause the required amount of liquid fuel to be fed into the cylinder of the engine at each operation of the plunger 30, the said plunger being operated in the manner and cooperating with other parts of the nozzle structure in the manner as hereinbefore described.

Assume now that because of some variation in conditions the speed of operation of the engine is increased or accelerated and that it is desired to decrease the speed of the same to the normal speed or a desired speed. In that case the lever 87 would be actuated or operated to turn the shaft 85 and the eccentric thereon in an anti-clockwise direction. Rotation in that direction would effect elevation of the outer end of the lever 83 and depression of the inner end thereof so as to adjust or move the inner end of the device 90 into nearer relation with respect to the adjoining end of the rod 50. It has already been pointed out that when the lever 70 is oscillated about its pivot 71 the inner end of the lever 83 moves with greater speed or acceleration than the adjoining portion of the said lever 70. If adjustment be made so that the device 90 is placed in closer relationship with respect to the end of the rod 50 the latter will be operated to open the valve 49 at a point or moment with relation to the inward movement of the plunger 30 in advance of that in which it has been previously opened. It previously has been explained that upon the opening of the valve 49 reverse flow of the liquid fuel is permitted so that immediate closing of the valve 17 is effected. It will be apparent therefore that a smaller quantity of fuel is introduced at each descending or charging movement of the plunger 30.

If, however, the conditions should be changed and the speed of operation of the motor decreased owing to increased load or other cause, additional fuel may be caused to be discharged into the cylinder at each descending movement of the plunger 30 by rotating the shaft 85 and the eccentric thereon in a clockwise direction to depress the outer end of the lever 83 and elevate the inner end thereof together with the device 90 carried thereby. Such adjustment of the device 90 will cause the valve 49 to remain closed for a greater part of the descending movement of the plunger 30 and

in consequence a greater amount of fuel will be introduced or discharged by the nozzle into the cylinder at each descending movement of the plunger. The supplying of a greater quantity of fuel will result in the production of greater energy and power whereby the speed of operation of the engine will or may be returned to normal.

By the means and the method of operation as hereinabove described the speed of operation of the engine may be effectively and practically controlled.

It will be seen that by my invention I have provided a means of simple construction for feeding or delivering liquid fuel to the cylinder or cylinders of an internal combustion engine structure under control and in a most efficient and economical manner.

Having thus described my invention, what I claim and desire to secure by Letters Patent is,

1. A device of the character described for the delivery of liquid fuel into the cylinder of an internal combustion engine, which device comprises a tubular casing having a fuel discharge opening at its inner end, a valve for closing the said discharge opening, a plunger located within the said casing which plunger includes a member the inner half part of which is provided with a relatively large axial opening into which liquid fuel is adapted to be delivered, a valve structure for controlling the discharge of fuel from the opening in said member, a rod having connection with a valve of the said valve structure and extending axially of the said member outwardly beyond the outer end thereof, yielding means tending to cause outward movement of said rod with respect to the said member, and means which is adapted to cause the said member and the said rod to move inwardly first as a unit and which thereafter causes the said rod to move inwardly more rapidly than the said member, and means whereby the unitary inward movement of the said member and the said rod operates to open the first named valve.

2. A device of the character described for the delivery of liquid fuel into the cylinder of an internal combustion engine, which means comprises a casing having a discharge opening at its inner end, a valve for closing said opening which valve is provided with a stem having an enlarged tubular portion located in the said casing, said tubular portion having openings in its lower end which communicate with the interior of the said valve casing, a plunger located within the tubular portion of said valve stem, said plunger comprising a member having a tubular portion, a rod extending through said tubular portion and terminating at its inner end in a valve, a movable

valve member supported upon said rod and located intermediate the valve thereon and a valve seat in the lower end of the tubular portion of the said plunger member, means tending to cause outward movement of the said rod means for supplying liquid fuel under pressure to the said tubular valve member, yielding means tending to hold the first named valve in closed position and the said plunger in outermost position, means for effecting inward movement of the said plunger, and means for thereafter effecting inward movement of the said rod member of the plunger relatively to the other portions of said plunger to permit reverse flow of fuel from the said casing into the tubular member of the said plunger whereby the said yielding means is permitted to effect closing movement of the first named valve.

In testimony that I claim the foregoing as my invention I have hereunto signed my name this 29th day of March, A. D. 1927.
